Patented Nov. 2, 1926.

1,605,100

UNITED STATES PATENT OFFICE.

EDWARD J. DINNEEN, OF OGDENSBURG, NEW YORK.

BOILER.

Application filed March 3, 1926. Serial No. 91,983.

My invention relates to hot water or steam boilers.

In accordance with my invention, I provide a boiler embodying a lower double walled section, constituting a fire box. A tube boiler is mounted upon this double walled section, and is supported thereby. The lower section is hollow and receives the water and is in communication with the water space of the tube boiler. The arrangement is such that the maximum heat exchange is effected.

In the accompanying drawings, forming a part of this specification, and in which like numerals are employed to designate like parts throughout the same,

Figure 1 is a central vertical longitudinal section through a boiler embodying my invention,

Figure 2 is a transverse section taken on line 2—2 of Figure 1,

Figure 3 is a perspective view of the lower double walled section,

Figure 4 is a transverse section through the double walled section, taken on line 4—4 of Figure 3, and,

Figure 5 is an end elevation of a modified form of double walled section.

In the drawings, wherein for the purpose of illustration, is shown a preferred embodiment of my invention, the numeral 10 designates a lower double walled section or shell, constituting the fire box of the boiler. This double walled section may be formed of material, such as steel or cast iron. This double walled section is suitably mounted upon a concrete foundation 11 and a bridge wall 12 is provided, affording a fire box 13 and combustion chamber, 14. The fire box 13 may be equipped with a grate 15 of the usual construction with an ash pit 16, therebelow. The double walled section is provided with a fuel door opening 17, to be covered by a suitable door 18.

The lower double walled section 10 is provided in its ends, and at the tops thereof, with semi-circular recesses 18' receiving and supporting the cylindrical shell or casting 19, of a fire tube type boiler. Substantially one-half of this shell projects above the recesses 18', as shown.

Arranged within the shell 19 and suitably spaced from the ends thereon, are flue plates 20 and 21, spaced from the ends or heads 22 and 23 respectively, as shown. The tubes or flues 24 are held within openings in the

heads 20 and 21, in the usual manner. The head 21 is spaced from the head 23 providing a smoke or gas chamber 24', at the forward end of the boiler. The head 20 is 60 spaced from the head 22 forming a smoke or gas chamber 25, in communication with the upper set of tubes 24, and the bottom of this chamber 25 is closed by a horizontal bridge 26, passing between the upper and 65 lower sets of tubes and separating the same. The shell 19 is provided with an opening 27 and adjacent to the horizontal bridge 26, whereby gases may pass from the chamber 14 into and through the lower sets of tubes, 70 at the rear ends thereof. These gases, of course, pass forwardly through the lower sets of tubes and then discharge into the chamber 24' and then pass rearwardly through the upper set of tubes 24, and finally discharged into the chamber or compartment 25 and then pass into the stack or chimney 28. Both heads 22 and 23 are detachable, providing access to the ends of all the tubes, for clearing, or for rolling the 80 ends of the tubes, whereby all the tubes may be removed without getting into the fire box. 75

The heated water from the sides of the double walled section 10 passes through risers 29, which lead into the shell 19, between the heads 20 and 21 exteriorly of the tubes 24. All of the tubes are of the same maximum length, and the heated gases pass forwardly through the lower tubes and rearwardly through the upper tubes, throughout 90 their entire length, before discharging into the stack, thus effecting the maximum heat exchange.

Cold water may be supplied to the lower portion of the double walled section 10, 95 through an inlet pipe 30. Steam passes from the shell 19, between the heads 20 and 21, through the pipes 31.

In Figure 5, I have shown the double walled section 10 as formed in two parts 10', 100 which are adapted to be connected by means of angle irons 11' which may be bolted together. The parts 10' are preferably formed separate so that they have no communication with each other. This construction is preferred when the boiler unit is to be built in a larger form as it permits the lower section to be separated in two parts, for the convenience of handling and installation.

It is to be understood that the forms of 110 my invention, herewith shown and described, are to be taken as preferred examples of the

same and that various changes in the shape, size and arrangement of parts may be resorted to without departing from the spirit of my invention or the scope of the subjoined claim.

Having thus described my invention, I claim:

A boiler of the character described, comprising a double walled lower section having 10 a fire box at its rear end and a combustion chamber at its forward end, said double walled lower section being provided at the tops of its ends with substantially semi-cylindrical transverse recesses, a cylindrical shell supported at its opposite ends within the substantially semi-cylindrical recesses, the entire area of the ends of the cylindrical shell being accessible from the exterior of the ends of the double walled lower section, tube 15 heads arranged within said shell and spaced from the ends of the same forming smoke boxes, tubes of the same length extending between and carried by the tube heads, detachable outer heads secured to the ends of 20 said cylindrical shell and covering the smoke boxes, a substantially horizontal bridgewall 25

arranged within the forward smoke box and dividing the same into upper and lower smoke box sections, the upper set of tubes communicating with the upper smoke box 30 section and the lower set of tubes communicating with the lower smoke box section, said cylindrical shell being provided in its forward portion with an opening to establish communication between the combustion chamber and the lower smoke box section, a stack leading into the top of the upper smoke box section, the gases passing from the gas chamber rearwardly through 35 the lower set of tubes and forwardly through the upper set of tubes and discharging into the stack, means of communication between the interior of the double walled lower section and the interior of the cylindrical shell, inlet means for the lower section, and outlet 40 means for the cylindrical shell, the outer detachable heads providing access to the opposite ends of the upper and lower sets of tubes.

In testimony whereof I affix my signature.

EDWARD J. DINNEEN.
